F. DOCHNAL

GARMENT SUPPORTER

Filed Sept. 18, 1922

Inventor:

Frank Dochnal

By: *Frank J. Hanson*
Attorney.

UNITED STATES PATENT OFFICE.

FRANK DOCHNAL, OF COLLINSVILLE, ILLINOIS.

GARMENT SUPPORTER.

Application filed September 18, 1922. Serial No. 588,832.

To all whom it may concern:

Be it known that I, FRANK DOCHNAL, a citizen of the United States, residing at Collinsville, in the county of Madison and 5 State of Illinois, have invented a certain new and useful Garment Supporter, of which the following is a specification.

My invention relates to garment supporters, and, more particularly to means for 10 gathering or taking up the slack at the waist line of oversize drawers, and, has for its object the provision of a distinct and practical improvement to overcome certain 15 practical objections to, and defects in, the present method of drawer waist line adjustments.

A further object of the invention is to provide a waist line adjusting means for 20 drawers, which, if desired, may be detachable and which will be simple in construction, cheap in manufacture, comfortable when worn and prove highly efficient for 25 the purpose intended.

A still further object of the invention is 30 the provision of elastic sections between the gripping means of the article to permit end-wise expansion thereof during various 35 movements of the wearer.

With the above and other objects in view, 40 as will be apparent hereinafter, the invention consists in the novel features of construction, arrangement and combination of parts hereinafter more fully described and 45 finally pointed out in the claims hereto appended.

Referring to the accompanying drawings forming a part of this specification, wherein like characters of reference denote similar parts throughout the several views:

40 Fig. 1, is a rear elevation of an article embodying the features of my invention, and shown in full lines as applied to the waist line of a pair of drawers, either sex, and showing in dotted lines, the fastening 45 straps before they are placed into operative position.

Fig. 2, is a longitudinal sectional view of the supporter applied to a garment.

Fig. 3, is a modification of the method of 50 applying one end of the article to the waist line of a garment.

Fig. 4, is a rear elevation of the modified 55 form of supporter applied to the waist line of a pair of drawers.

In carrying out the aim of my present invention, I employ a non-elastic central mem-

ber 1, such as metallic, leather, cloth or equivalent material and provide the same with a vertically disposed slotted, or elongated button receiving opening which is 60 larger in diameter at its upper end designated 2, than at its lower end designated 3. A suitable flexible fastener, or gripper strap 4 is suitably fixed to, or, if desired, may be integral with the upper edge of the central 65 supporter member 1. A button 5, with or without a shank 6, as desired, is suitably fixed to the inner face of the strap 4 near its free end. The strap 4 is of such length as to fold over the upper edge 7 of a waist 70 band 8 of a garment 9 and engage the inside of the garment waist band and to permit the button, as well as a portion of the garment designated 10, which engages and 75 covers the outer face of the button, to be received by the enlarged upper end 2 of the button hole of the central supporter member 1 and moved downwardly into engagement with the smaller end of the button hole designated 3 to securely hold the central 80 member 1 of the supporter upon the waist band 8 of the garment 9.

It will be observed that in forward bending and various other movements of the wearer, the button and its covering of fabric garment material will more tightly engage in the slotted opening.

An elastic fabric section 11 of suitable length, is suitably fixed at one end to each end of the central flexible garment gripping 90 member 1, such as by sewing stitches 12, or by equivalent fastening means.

In the preferred embodiment of my invention, a garment gripping device is carried by the outer end of each elastic section 95 11, and each of said devices consist of a non-elastic end member 13, each having a longitudinally disposed slotted opening 14 narrowing into the passage 15 at its outer end and terminating in the button receiving 100 opening 16. The members may be made from metal stampings, wire, leather or equivalent material, as desired. A flexible fastener or gripper strap 17 is suitably fixed to, or integral with the upper inner end portion of each end member 13. These straps 105 preferably diverge from the end members 13 and are provided upon their inner faces near their free ends with a suitable button 18, which may, or may not be provided with a shank 19, as desired. These diverging 110 straps 13 are of such length as to fold over

the upper edge 7 of the waist band 8, of the garment 9 to permit the buttons 18, as well as portions of the garment designated 20, which engage and cover the outer face 5 of the buttons 18, to be received by the enlarged elongated openings 14 and finally moved outwardly into locking engagement with the openings 16.

When the waist band of the garment, 10 such for instance as a pair of drawers, is too large for the wearer, the central gripping device for convenience now designated A is first positioned and removably fixed to the center of the back portion of the garment and to the waist band thereof, as 15 clearly shown in Fig. 1. After the supporter has been positioned, the wearer gathers the surplus goods of the waist band 9 upon one or either side of the center 20 gripping device A, as designated 20' sufficient to shorten the band circumferentially to properly fit the wearer, and, then the end gripping devices for convenience, now designated B, are applied to the garment as 25 hereinbefore described, so as to prevent the gathered portions of surplus material designated 20' from expanding excepting as will be permitted during various bending movements of the wearer through the medium of 30 the elastic sections 11.

As shown in Figures 1 and 2, the supporter is easily and quickly applied or detached from a garment, as it is merely buttoned to the garment.

35 In Figures 3 and 4, I have shown a modified form of supporter wherein I eliminate one of the gripping straps 17 and suitably fix the end section 13 to the waist band 8 of the garment, which may be varied in shape 40 and size, by sewing stitches 22, or by equivalent fastening means. In the modified form of supporter, the article remains a part of the garment, whereas in the form shown in Figures 1 and 2, the supporter can be 45 quickly applied to a garment, and detached therefrom, and applied to another garment if desired.

Briefly, the supporter will permit the gathering of surplus waist band material of 50 a pair of drawers, or like garment, as clearly shown in Figures 1 and 2, and hold the surplus material in gathered formation upon one, or both sides of a central gripping device, thus causing the waist band to be 55 adjusted to fit the wearer if too large, and holding the waist band to its adjusted size, as taken up by the gathering of the material thereof.

60 From the foregoing description, it is evident that I provide a supporter for garments, which can be quickly applied for taking up the slack in oversize garments at the waist band so as to properly fit the wearer thereof.

65 The many advantages of the herein described invention will readily suggest them-

selves to those skilled in the art to which it appertains.

I do not wish to be understood as having limited myself to the exact details of construction shown and described, but desire 70 to have it understood that the invention I have shown in the drawings is merely illustrative, as it is manifest that various minor changes may be made in the exact construction and particular arrangement of parts 75 without departing from the spirit of my invention, hence I reserve the right to make any such changes, or modifications as may fairly fall within the scope of the appended 80 claims when fairly construed.

What I claim is:

1. In an article of the class described, central gripping means comprising a central member having a transversely disposed slotted opening larger in diameter at its upper 85 end than at its lower end, a strap member provided with a button for slidable reception within said opening when applied to a garment, and gripping means comprising a pair of opposed end members each having 90 a longitudinally disposed slotted opening larger at one end than at the other end and a strap member for each end member provided with a button for slidable reception in said slotted openings when applied to a 95 garment and an elastic connection between each end member and the central member for gathering the attached garment upon opposite sides of the central gripping means to tighten the waist line thereof. 100

2. A garment waist line takeup supporter comprising a centrally disposed garment gripping means comprising a slotted member and an attached strap member provided with a button adapted to be applied to the 105 waist band of a garment at a convenient point, end garment gripping means comprising a pair of opposed slotted members each having an attached strap member provided with a button adapted to be applied to the 110 garment after surplus waist line material has been gathered upon either side of the central gripping means to adjust the waist band of the garment to the size of the wearer and elastic connections between the central 115 gripping means and each end gripping means to permit of endwise expansion of the supporter during various movements of the wearer.

3. A garment supporter comprising a central clasp member provided with a slot, a flexible strap fixed to the upper edge of 120 said central clasp member, a button fixed to the flexible strap and slidably receivable in the slot of the central clasp member, an elastic band fixed to and extending from the side edges of said central clasp member, an end clasp member provided with a slot 125 fixed to the outer end of each elastic member, a flexible strap member fixed to each end 130

clasp member, and a button fixed to each strap member, said buttons each being slidably receivable in the slot of its respective clasp member.

- 5 4. A garment supporter comprising a central body member provided with a slotted opening, a strap fixed to said body member, a headed stud fixed to said strap and slidably receivable in said slotted opening, a 10 pair of opposed elastic members fixed at one end to the side edges of said central body member and extending in opposite directions, a clasp member fixed to the free end of each elastic member and each consisting of a body member having a slotted opening, a strap member for each body member and a headed stud fixed to the free end of each strap member and slidably receivable in the slotted opening of its 15 respective body member.

5. A garment supporter comprising a flexible central member, flexible end members and elastic intermediate connecting members, said flexible members each having a slotted opening formed therein larger in diameter at one end than at the other end, a strap member for each flexible member and a button carried by each strap member slidably receivable in the slotted openings of its respective flexible member for attaching a garment in fixed relation thereto.

6. A supporter for drawers comprising a central member having a transversely disposed slotted opening, a strap fixed to the upper edge of said central member, a button for said strap and slidably receivable in the slotted opening of said central member, a pair of end members each having a longitudinally disposed slotted opening, a strap for each end member, a button fixed to each end strap and slidably receivable in the slotted opening of its respective end member and an elastic connection between the central member and each end member 40 to permit circumferential expansion of the supporter when applied to the waist band of a pair of drawers for the purpose of

taking up the slack or surplus material at the waist line when too large for the wearer.

7. A supporter for drawers comprising a central member having a transversely disposed slotted opening to lie at the outside of the garment, a strap member fixed to the upper edge thereof, a button carried at the free end of said strap member, said strap member adapted to fold over the upper edge of the waist band of the garment with the strap lying at the inside of the garment, and with the button and material of the garment engaging the button engageable in the slotted opening of the central member, and fastening means adapted to be removably fixed to the garment at suitable distances from the central member after the surplus material of the waist band of the garment has been gathered upon one or both sides of the central member and elastic connections between the central member and the end fastening means.

8. A garment supporter comprising a central body member provided with a transversely disposed slotted opening larger in diameter at its upper end than at its lower end, a strap fixed to said central body member, a headed stud fixed to said strap and slidably receivable in said slotted opening for holding a garment in fixed relation thereto, a pair of opposed elastic members fixed at their inner ends to the side edges of said central body member and extending in opposite directions therefrom, a clasp member fixed to the free end of each elastic member and each clasp member consisting of a body member having a longitudinal slotted opening larger in diameter at their inner ends than at their outer ends, a strap member for each body member and a headed stud fixed to the free end of each strap member and slidably receivable in the slotted opening of its respective body member for holding a garment in fixed relation thereto.

In testimony whereof, I have hereunto signed my name to the specification.

FRANK DOCHNAL.
